UNITED STATES PATENT OFFICE.

GUSTAF OLSON, OF CHICAGO, ILLINOIS, ASSIGNOR OF ONE-HALF TO WILLARD M. McEWEN, OF CHICAGO, ILLINOIS.

FLUID-PUMP.

1,338,839.

Specification of Letters Patent. Patented May 4, 1920.

Application filed January 4, 1917. Serial No. 140,543.

To all whom it may concern:

Be it known that I, GUSTAF OLSON, a citizen of the United States of America, and a resident of Chicago, county of Cook, 5 and State of Illinois, have invented certain new and useful Improvements in Fluid-Pumps, of which the following is a specification.

This invention relates to fluid pumps of 10 the type wherein the rotor is eccentrically mounted in the casing and carries vanes adapted to subdivide and traverse a chamber formed between the casing and the periphery of the rotor, for the purpose of compressing and expelling the fluid contents 15 of said chamber. A device of this type is more fully described and claimed in my pending application, Serial No. 119,462, filed September 11, 1916, and of which the 20 subject matter of this application constitutes in many respects an improvement.

The main objects of this invention are to provide an improved construction and arrangement of the casing affording improved 25 means for cooling the pump; to provide an improved mounting of the rotor in the casing; and to provide improved means for controlling the vanes and holding them into contact with the wall of the compression 30 chamber during the travel therethrough.

An illustrative embodiment of this invention is shown in the accompanying drawings, in which—

Figure 1 is an end elevation, partly sectional, of the improved fluid pump.

Fig. 2 is a side elevation, partly sectional, of the same.

Fig. 3 is a sectional detail of the inner casing ring or shell.

Fig. 4 is an end view of the same.

Fig. 5 is a sectional detail of the outer casing ring or shell.

Fig. 6 is an end view of the same.

Fig. 7 is an end view of the rotor.

Fig. 8 is a fragmentary plan of the same.

Fig. 9 is an end view of one of the disk members which is a part of the means for causing the reciprocation of the vanes.

Fig. 10 is a sectional detail of the same.

Fig. 11 is an end view of one of the casing end plates.

Fig. 12 is a sectional detail of the same.

Fig. 13 is a perspective view of one of the vanes.

Fig. 14 is a detail view, partly sectional,

illustrating the mounting of the rotor shaft on the eccentric bearings which in turn support the disks, one of which is shown in Fig. 9.

In the construction shown in the drawings, the casing is made up of outer and inner rings or shells 1 and 2 arranged one within the other and having the ends thereof closed by means of end plates 3 and 4.

The outer ring or shell is provided with 65 base supports 5 upon which the device is adapted to rest, and the bore thereof is substantially perfectly cylindrical and provides an air-tight fit with the outer periphery of the inner shell or ring 2 when 70 the two are assembled.

The inner ring 2 has an annular recess formed in the outer periphery thereof, between the ends of the ring, which extends nearly all the way around so as to provide a 75 cooling chamber 6 within said casing. The oval-shaped bore of the inner ring 2 is a composite formation of two eccentrically arranged bores providing an approximately semi-cylindrical wall 7 formed with its 80 center at 8 and an approximately semi-cylindrical wall 9 formed with its center at 10. The radius of the wall 9 is somewhat larger than the radius of the wall 7, so that the peripheral length of the former is 85 greater than that of the latter, as will be more readily observed from Figs. 1 and 4.

The end plates 3 and 4 are adapted to be attached to the inner ring or shell 2 by means of screws 11 so as to form closures 90 for the bore of the inner ring and also serve as bearing supports for the rotating parts of the pump.

The rotor 12 is journaled in the ring 2 on an axis coincident with the center 8 so that 95 the periphery of said rotor fits with the corresponding annular wall 7 and provides a space 13 between the periphery of said rotor and the other annular wall 9. This space constitutes a compression chamber 100 which is transversed by vanes 14 during the rotation of the rotor 12 so that the air is drawn in at one end thereof, compressed and discharged at the opposite end, as will more fully hereinafter appear. The rotor 12 is rigidly mounted on a shaft 15 and has formed therein a plurality of radially disposed slots 16 in which the vanes 14 are reciprocatingly mounted.

The reciprocation of the vanes 14 is 110

effected by means of disk members 17 co-
acting with lugs 18 formed on the ends of
the vanes 14 and carrying bearing mem-
bers 19 slidably mounted in annular grooves
20 formed in the inner faces of said disk
members. The disk members 17 are rotatably
mounted in recesses 21 formed in the inner
faces of the end plates 3 and 4 and at the
same time journaled on bearings 22. The
bearings 22 are in the form of stud shafts
rigidly secured in said end plates on an axis
coincident with the center 10 so that said
stud shafts are obviously eccentrically ar-
ranged with respect to the shaft 15 which
they rotatably support. The annular
grooves 20 formed in the inner faces of the
disk members 17 are of course concentric
with the axis of rotation thereof, so that as
the rotor 12 revolves and the distance be-
tween the axis thereof and the grooves 20
increases and decreases, the vanes 14 are
caused to shift outwardly and inwardly re-
spectively for the purpose of keeping the
ends thereof in contact with the annular
wall 9 as said vanes are being moved
through the compression chamber 13. Being
thus supported at both ends, the reciproca-
tion of the vanes 14 is very positive and is
effected with very little friction.

30 The admission of fluid to and the dis-
charge thereof from the compression cham-
ber 13 are through the inlet ports 23 and
24 respectively. These ports are in the na-
ture of threaded openings so formed in op-
posite sides of the rings 1 and 2 that when
the rings are assembled, the openings come
into alignment and permit pipes or other
fittings 25 to be screwed entirely through
the openings in the ring 1 and into the
aligned openings in the ring 2 so that said
fittings bridge the joint between the rings,
as is indicated in Fig. 1. This readily in-
sures a fluid-tight connection with the com-
pression chamber 13. Recesses 26 and 27
45 are formed in the inner periphery of the
ring 2 adjacent to the inlet and outlet ports
so as to increase the communication between
the ends of the compression chamber 13 and
the respective inlet and outlet ports 23
50 and 24.

Inlet and outlet ports 28 and 29 are
formed in one side of the ring 1 so as to
connect with opposite ends of the cooling
chamber 6 formed between the rings 1 and
55 2, as hereinbefore explained. The cooling
medium used in the cooling chamber 6 may
be either air or water, or some other liquid,
as may be found most convenient under the
circumstances met with in practice.

60 When using air as a cooling medium, it
has been found expedient to connect the out-
let port 29 with the inlet port 23 which con-
nects with the compression chamber, so that
the air taken into the compression chamber
65 is first drawn through the cooling cham-

ber 6, thus facilitating the cooling of said
pump. A suitable conduit 30 made up of
the usual pipe fittings may be used for con-
necting these ports, as illustrated in Fig. 1.

The operation of the device shown is as follows:

A pulley or other driving means (not
shown) is attached to the shaft 15 and con-
nected with a source of power. The rotor,
being rigid on the shaft 15, and the disk 75
member 17, which is connected to the rotor
through the medium of the vanes 14, are
caused to rotate about their respective axes.
These axes being eccentric, the vanes 14 are
caused to move back and forth in their re-
spective slots in the rotor 12 and are held
in firm contact with the annular wall 9 as
they are moved through the compression
chamber 13. As the vanes move through
the compression chamber 13, fluid is drawn 85
in through the inlet port 23 into the space
at the rear of each of the vanes, and as the
vanes approach the opposite end of the
compression chamber, it is compressed and
discharged through the outlet port 24. 90
Thus, as the pump is caused to rotate, it
supplies to the desired point a substantially
continuous compressed supply of the fluid.

Although but one specific embodiment of
this invention has been herein shown and
described, it will be understood that nu-
merous details of the construction shown
may be altered or omitted without depart-
ing from the spirit of this invention as de-
fined by the following claims.

I claim:

1. In a device of the class described, the
combination of a casing having an annular
cooling chamber formed therein and ex-
tending almost entirely therearound, inlet 105
and outlet ports connecting with the oppo-
site ends of said cooling chamber, a rotor
journaled in said casing so as to form a
compression chamber, a plurality of radi-
ally movable vanes carried by said rotor,
inlet and outlet ports formed in said cas-
ing and communicating with the opposite
ends of said compression chamber, and
means connecting the outlet port of said
cooling chamber with the inlet port leading 110
to said compression chamber.

2. In a device of the class described, the
combination of a casing comprising sepa-
rate inner and outer rings concentrically ar-
ranged one within the other in air-tight 120
contact, said casing having an annular cool-
ing chamber formed therein between the op-
posed faces and extending almost entirely
around said inner and outer rings, inlet and
outlet ports connecting with the opposite 125
ends of said cooling chamber, said inner
ring having an oval-shaped bore, a rotor
journaled in said casing whereby the pe-
riphery of said rotor fits with a part of the
wall of said bore and provides a space be- 130

tween the periphery of said rotor and another part of the wall of said bore adapted to serve as a compression chamber, a plurality of radially movable vanes carried by said rotor, means for urging said vanes into contact with said other part of the wall of said bore as said vanes are caused to traverse said compression chamber, inlet and outlet ports formed in said casing and con-

necting with the opposite ends of said compression chamber, and a conduit connecting the outlet port of said cooling chamber with the inlet port leading to said compression chamber.

Signed at Chicago this 30th day of December, 1916.

GUSTAF OLSON.
